UNITED STATES PATENT OFFICE.

LUTHER K. JEWETT, OF FITCHBURG, MASSACHUSETTS.

WRECKING AND CONSTRUCTION CAR FOR RAILROADS.

SPECIFICATION forming part of Letters Patent No. 252,672, dated January 24, 1882.

Application filed October 31, 1881. (No model.)

To all whom it may concern:

Be it known that I, LUTHER K. JEWETT, of Fitchburg, county of Worcester, State of Massachusetts, have invented an Improvement in Wrecking and Construction Cars for Railroad Work, of which the following description, in connection with the accompanying drawings, is a specification.

This invention has for its object the construction of a car for wrecking or lifting cars which have been derailed, and also for handling heavy articles in railroad construction.

In this my invention I have provided a car with a tipping counterbalanced mast and connected boom, and have shown the said mast, as I prefer, mounted directly on a turn-table carried by the said car, such construction enabling me to use a mast longer than would be possible were the said mast always held in an upright position, for when the wrecking-car is being moved on the track the mast is turned down in nearly horizontal position, thus enabling the car to readily pass under bridges. As soon as the car is brought in position near a wreck, or on a part of the track when the car is to be used, the car is locked to the track, its frame is braced so that it cannot sag or tip, a suitable strong step for the mast is brought into position, the mast is released, turned into an upright position with its lower end on the said step, and the turn-table is braced or secured so that it has only a rotating movement. In this condition the car is in readiness to have the boom turned down, and, with the usual ropes, chains, and grappling-hooks, be used to lift into position the car to be handled. In connection with the car I have provided a series of braces to afford additional strength and stability to the car when a wrecked car is to be lifted from a ditch up a steep embankment.

Figure 1 represents in side elevation a car embodying my invention as it will appear when running on the track, the dotted lines, however, showing the mast elevated and boom turned out, the said figure also showing in dotted lines the leveling-blocks, which will be laid on the ties to receive the lower ends of the jack-screws when the car is brought to rest and the mast is elevated. Fig. 2 is a vertical longitudinal section of the car with the mast elevated, its foot being supported on the step.

Fig. 3 is a top view of Fig. 2; Figs. 4 and 5, partial cross-sections of the car, the parts being enlarged and in different position of adjustment; Fig. 6, a top view of the step for the mast and the step-sill; Fig. 7, a section of Fig. 6; Fig. 8, a partial end view, showing the car as braced to take a wrecked car from a ditch at the left; and Fig. 9, a side elevation thereof, the mast and boom being, however, omitted.

The car-body A, of suitable shape to support the working parts, is mounted on suitable trucks, not necessary to be described, which run on the track as usual. The car-body, in practice about twenty feet long, is provided substantially at its center with a strong ring, b, having journals 2, mounted in bearings a², held on the side sills of the car, the central part of the car below and about the said ring being open. This ring at its front and rear sides has flanges a³, (shown clearly in Fig. 2,) under which may be moved the ring-timbers a⁴ when it is desired to hold the ring so that it cannot tip or turn on its journals, it being necessary to hold the ring firmly when the car is being used to lift a wrecked car. When the car is being run on the track and the mast b is turned down, as in Fig. 1, the ring-timbers are removed from below the flanges of the ring a, permitting the ring to be tipped up at one end, as shown. The top of this ring, made flat, serves as a track for the anti-friction wheeled ring c, (shown clearly in Fig. 2,) which is interposed between the turn-table d and the ring a, the wheeled ring c sustaining the turn-table on the ring a, permitting the turn-table to be easily moved to enable the boom b' of the mast to be projected in any desired direction from the car A. These ring-timbers a⁴ are shown as provided with worm-gears a⁵, which engage each with the teeth of a worm-rack, such as shown at a⁶. By turning the worm-gears in one of the other direction, their teeth acting on the said rack, the ring-timbers may be moved under or from under the ring a. Each timber will have two gears, a⁵, and each gear will have on its shaft a chain-wheel, a¹⁶, to receive a suitable chain, rope, or cord connected with a shaft, a⁸, which, when rotated in one or the other direction, will move the chain or cord and turn the worm-gear simultaneously in the proper direction to move the ring-timbers in the direction

desired. The turn-table at its lower side has a depending annular collar, which fits inside the ring a .

The mast b is rigidly connected with the turn-table d , and at its lower end is provided with a connected counterbalancing-upright, b^2 , in practice of several tons. The lower end of this weight b^2 serves as the foot for the upright mast, and in practice will be made to rest upon the step e , as shown in Fig. 4.

The step e is shown as provided with journals 4 , (see Fig. 6,) which rest upon a step-bearing, e^2 , made adjustable vertically at each end with relation to the step-sill e^1 by means of screws e^3 , and made horizontally adjustable by means of the screws e^5 . The step-sill e^1 is suitably secured to the track so that it cannot move, and by adjusting the screws e^3 the step e may be more or less raised to cause it to receive and sustain more or less of the weight of the mast and turn-table.

To prevent the mast from being tipped out of vertical position I have provided it, at its lower end, with a locking device, f , (shown in Fig. 2,) as a pin connected with an arm of a rock-shaft, f^2 , another arm, 5 , of the said rock-shaft being joined with a link or rod, f^3 , extended above the turn-table, to thus permit the locking device to be lifted or moved at the proper times.

The mast has pivoted upon it a boom, b' , which may be of any usual construction. This boom will be raised and lowered through a rope or chain, h^3 , on a drum or windlass, h^2 , operated in any usual manner. Suitable other chains and grapples will be attached, as usual, to the end of the boom to be connected to the car or other thing to be lifted. Supporting the mast, as described, on the car so that it may be turned or tipped down enables me to use a long mast, one which could not be used if connected with and extended rigidly above the car-body, for when turned down it does not interfere with the passage of the car under bridges. The mast b is made of such length as to permit me to grapple a car or car-body and readily lift it at one operation high enough to be swung onto a flat car on the track ready to be taken away.

The end and side sills of the car A have connected with them a series of jack-screws, g h i j . The screws g are pivoted to the corners of the car, and those h a short distance therefrom on the side sills. These screws g h are made to rest upon the leveling-blocks g^2 , laid upon the ties g^3 , outside the rails g^4 , the said leveling-blocks being placed in position when the car is brought to rest, the screws g h being then turned in to prop or steady the car, so that it cannot tip or sag. The screws i are connected with the side sills of the car near their centers, and act upon the ends of the step-sill e^1 , as shown in Figs. 4 and 5, to confine the step-sill to the track and prevent the central part of the car from sagging. These screws i have long heads, which are extended through the ends of the step-sill, and have suitable nuts and washers or collars connected

therewith below the step-sill, so that when it is desired to run the car on the track the said screws may be moved to lift the step-sill from contact with and above the track, the step-sill being thus permanently connected with the car.

With a heavy car at the side of a track in a ditch or down an embankment, the wrecking-car must frequently be braced laterally, or at its side next the wreck. To do this effectively the car has as part of its equipment a ground-timber, l . (Shown in Figs. 8 and 9.) Upon this is mounted a brace, l^2 , preferably made extensible in the direction of its length. This brace l^2 has at its top guides m , which receive and hold a track-timber, m^2 , which is long enough to extend beyond the opposite side of the track, as in Fig. 8, where it and another like track-timber resting on a like brace, l^2 , are joined by means of a coupling, m^3 . These track-timbers m^2 , at their under sides, are provided with suitable metal chairs to fit over and embrace the tracks. The lower ends of the braces l^2 each have a jack-screw, l^3 , by which to lift them and the track-timbers supported by them to their proper level, and the braces also have locking-pins l^4 to prevent lateral movement.

The coupling m^3 for the end of the track-timbers next the wreck supports a jack-screw, n , the upper end of which comes in contact with a post, n^2 , having a head, n^3 , and a shoulder, n^4 , the latter engaging the under side of the side sill of the case, so that as the jack-screw n is turned it lifts and at the same time presses the post against the side of the car.

The provision of side braces for the car, as shown in Figs. 8 and 9, insures the greatest steadiness for and enables the car to be maintained securely in position on the track, notwithstanding the boom is projected at right angles from the car, and strain at such time on the boom tends to turn the car over. Were it not for these side braces a heavy weight or body could not be lifted from a ditch at the side of the car by means of a single car. The braces increase the efficiency of the car over fourfold, as I have found in practice. The jack-screw n may be used without the track-timbers and braces, the coupling m^3 then resting on any suitable flat timber.

The step-sill e^1 may be braced laterally by the braces p , the ends of which are guided on pins p^2 , so that the braces can rise and fall with the step-sill as it is raised and lowered.

The mast, when turned down as in full lines, Fig. 1, by the employment of suitable tackle, will be locked in such position in any suitable way—as, for instance, the pin f may be made to rest on the top of the cross-beam r of the car.

I claim—

1. The combination, with the car, of a pivoted mast provided with a boom, counterbalanced mast b b^2 , provided with a pivoted boom, b' , the mast being adapted to be turned down nearly horizontally when the car is to be run on the track, substantially as described.

2. The car and the weighted or counter-

balanced mast and its turn-table, combined with the pivoted ring a , substantially as described.

3. The car and the pivoted ring a to support the mast, combined with the ring-timbers to lock the ring a , substantially as described, when the mast is to be retained in upright position.

4. The car and counterbalanced mast, pivoted ring to support the mast, and the step-sill, combined with a locking device to engage the lower end of the mast with the step-sill, substantially as described.

5. The car and its attached rack a^6 and the pivoted ring a , combined with the ring-timbers, their worm-gears, and the cords or chains connected with the shaft of the worm-gears to operate them and the ring-timbers, substantially as described.

6. The combination, with the car, of the jack-screws g , pivoted to the corners of the car, substantially as described.

7. The combination, with the car, of the jack-screws g h , pivoted thereto, substantially as described.

25 8. The combination, with the car and its pivoted jack-screws, of the leveling-blocks g^2 ,

adapted to be sustained by the ties, substantially as described.

9. The car and turn-table and tipping mast, combined with the step-sill, step thereon, and means, substantially as described, to adjust the step on the step-sill.

10. The car, turn-table, and tipping mast, combined with the step, step-sill, and jack-screws connected with the car and with the step-sill, to operate substantially as described.

11. The car, its tipping mast, and boom combined with the track-timbers m^2 , post, n^2 , and jack-screw n , to operate substantially as described.

12. The car, its tipping mast, boom, and turn table, combined with the track-timbers m^2 , braces l^2 , and suitable screws to hold the said braces and car in proper position, substantially as described.

In testimony whereof I have signed my name to this specification in the presence of two subscribing witnesses.

LUTHER K. JEWETT.
